CABLE OPERATED TRACTOR GATE

Phillip A. Kinzie, John L. Savage, and Warren H. Kohler, Denver, Colo., assignors to Universal Hydraulic Corporation, Denver, Colo., a corporation of Colorado

Application December 28, 1935, Serial No. 56,419

8 Claims. (Cl. 251—56)

This application relates to roller-mounted gates, such as are employed to control the flow of a fluid from a reservoir into an orifice for a penstock or conduit. In general, this application relates to 5 roller-mounted gates which are located on the upstream face of a dam and which are raised and lowered vertically by means of a cable hoist. More particularly, this invention relates to gates employing dual, oval-shaped roller carriage elements 10 which have a sloping plane parallel with a sloping plane on the gate leaf member for the purpose of producing lateral motion of the leaf when relative motion is produced between the roller carriage elements and the leaf member. Further, this invention relates to a method of controlling the 15 relative motion of the roller carriage elements and gate leaf member by an arrangement of the hoisting means for said parts.

Previous embodiments of the principle of seating 20 ing employed herein are described in application by Phillip A. Kinzie, filed February 8, 1933 (Serial No. 655,803) and by Phillip A. Kinzie, et al., filed December 28, 1935 (Serial No. 56,418).

Inasmuch as it is advantageous to be able to 25 inspect, paint, or service a gate without completely withdrawing the gate from active service, this gate is so constructed that it can be installed on the upstream face of a dam and raised above the reservoir water surface for the reasons hereinbefore 30 enumerated. A rigid stem would preclude lifts, such as are necessary for raising the gate unit above the reservoir level; therefore, a more convenient and flexible hoisting means must be employed. A cable satisfies these requirements, but 35 because of the principle of seating employed on this gate, the proper relationship between the gate leaf and roller carriages must be accurately controlled at all times. The sloping planes on the roller carriage elements and on the gate leaf member produce a vertical component which tends to 40 roll the leaf member upward along the roller carriage elements when greater water pressure is present on the upstream face of the gate leaf member than is present on the downstream face 45 thereof. This condition is most acute when the gate leaf is down and before it has been moved against the orifice seats; for in this position the water will have receded from the downstream face of the gate leaf leaving only atmospheric pressure 50 thereon, whereas the upstream face will be subjected to the reservoir head pressure. In order to overcome the tendency for the gate leaf member to roll up the sloping plane on roller carriage elements, it is necessary to be able to lift the gate 55 leaf and at the same time exert a downward pres-

sure thereon; or, stated in different words, it is necessary to exert a separating force between the gate leaf member and roller carriage elements. Further, it is necessary that a means whereby relative motion between the gate leaf member 5 and the roller carriage elements can be obtained for the purpose of seating the gate leaf.

We have simply and positively overcome this paradoxical obstacle—that of holding the gate leaf down while raising or lowering the unit by 10 flexible means—by the use of either levers or auxiliary sheaves, and by a manner of arranging the hoisting cables. Both methods which are shown and described herein are dependent only upon the hoist for their operation. The means by which 15 the foregoing, as well as the following, objects are attained will be fully described herein.

Our invention has as an object, a means for interrupting the flow of a fluid into an orifice from a fluid retaining reservoir by a roller-mounted 20 leaf member, raised and lowered vertically by a cable hoisting element.

Our invention has as an object, a cable hoisting means which will raise and lower a roller-mounted gate unit and which will maintain all 25 parts of said unit in their proper relationship.

Our invention has as an object, a cable hoisting means which will exert a separating force between the elements comprising a gate leaf and 30 roller carriages.

Our invention has as an object, a cable hoisting means which will produce a separating force between the elements of a gate leaf and the elements of dual roller carriages wherein, lever arms, pivoted on a crosshead member connecting the 35 roller carriage elements, and having sheaves mounted on one end thereof and having the opposite ends thereof connected to the gate leaf member by linkage, will produce said separating force.

Our invention has as an object, a squaring 40 means whereby the movement of dual lever arms can be synchronized by gear segments integrally mounted on said lever arms.

Our invention has as an object an arrangement of sheaves and a manner of reeving a hoisting rope 45 thereon which will produce a separating force between the elements comprising a gate leaf and roller carriages.

Our invention has as an object, a means for maintaining a crosshead member parallel with a 50 gate leaf member by the use of dual racks and pinions.

Our invention has as an object, a means for inducing a separating force between a gate leaf member and dual roller carriage elements, which 55

will form an integral part of the gate unit and which will be dependent solely upon a hoisting cable for its actuation.

Our invention has as an object, the arrangement of a gate installation wherein the gate unit can be raised above the surface of the water retained in a reservoir for the purpose of inspection, painting, and maintenance.

Our invention has as an object a means whereby the downward components produced by fluid flow beneath the bottom of a gate leaf member can be minimized by the shape of the bottom of said gate leaf.

Our invention has as an object, a means whereby roller-mounted sheaves may be immersed in a fluid without having said fluid enter the bearing surfaces thereof.

Our invention has as an object, a hoisting means for a roller-mounted gate unit wherein the cable hoisting medium therefor is not immersed in water while the gate is in service in the raised position.

To make clear the manner by which we attain these objectives and to satisfy the patent statutes, there will now be described the specific embodiments of the invention which have been illustrated in the accompanying drawings forming a part hereof, and wherein:

Fig. 1 is a sectional elevation of the upstream face of a dam showing the general arrangement of a gate leaf and hoisting elements.

Fig. 2 is a section taken on the plane 2—2 of Fig. 1.

Fig. 24 is a section taken on the plane 24—24 of Fig. 23.

Fig. 25 is a section taken on the plane 25—25 of Fig. 23.

In the accompanying drawings, Figs. 1 to 21 inclusive illustrate one complete embodiment of the invention, and Figs. 22 to 25 inclusive illustrate an alternate method of construction for the crosshead. In the accompanying description identical elements of both constructions will be designated by the same reference numerals.

By reference to Figs. 1, 2, and 3 it will be seen that the gate leaf 1, crosshead 2, and roller carriages 3 are raised by the hoist 4 through the medium of the hoisting cable 5.

The hoisting cable 5 is wound on the grooved, twin drums 6 (Figs. 4, 5, 6 and 7) which are turned by the pinion 7 and ring gear 8 which is integrally mounted between the twin drums 6. The synchronized motor and integral speed-reduction units 9 which drive the pinion shaft 10 through the flexible couplings 11 impart to the drums the torque necessary for raising the gate 1, crosshead 2, and roller carriages 3. The solenoid brakes 12, which are mounted directly on the outwardly extending ends of the motor shafts, provide a positive means of stopping the gate in any desired position. These solenoids are so constructed that they exert a braking force on the motor shaft at all times except when electric energy is turning the motors; further, their size is kept to a minimum because of their being connected to the motor shaft, an arrangement which allows relatively low capacity solenoids to positively sustain the gate in any desired position or prevent its dropping in the event of power failure. The indication and control unit 13 limits the travel of the gate leaf 1 and gives both direct and selsyn indication of the gate position.

The outwardly extending trunnion shafts 14 on the outwardly facing heads of the twin drums 6 are journaled in the bearings 15 which in turn are supported on the hoist frame 16. The pinion shaft bearings 17 are also supported on the hoist frame 16 as are the motor and speed reduction units 9, the solenoid brakes 12, and the gear guard 18. The hoist frame is anchored to the floor of the recess in the dam 19 and has its overhanging portion supported on the braces 20.

Inasmuch as the lift of gates in many cases requires several layers of cable to be wrapped on the drums, the added precaution of providing an automatic cable winding unit 21 (Figs. 4 and 7) has been taken. This device is driven by an auxiliary set of gears on the pinion shaft 10 which drive the shaft 22. The cable feeder units 23 are driven by dual threaded shafts 24 extending to the outward extremity of both drums from the unit 21. A dual set of guide sheaves 25 which are mounted on the cable feeder units 23, and between which the cable 5 is threaded, guide the cable on the drums evenly. A more complete description of this device will be made on an application in the future and the means by which reversing of the rotation of the threaded shafts 24 will be fully disclosed.

The gate leaf 1 (Figs. 8 and 9) is built up of I beam sections 26. The ends of the I beams are attached to the side plates 27 (Figs. 11, 12, and 14) by clip angles and are further secured at 70 their outward ends by the vertical channels 28. A vertical bar 29 together with the sloping bars 30 tie the outstanding flanges of the I beams 26 together. The skin plate 31 is bolted to the downstream flange of the I beams 26 (Figs. 11 and 75

12), and a sloping plate 32 in which the holes 33 are cut is attached to the bottom beam. The flat portion of the bottom likewise has holes 34 cut therein, and is stiffened by the web plates 35 in 5 which the holes 36 are cut. The sloping bottom and holes perform a function which will be hereinafter described.

The side frames 37 (Figs. 9, 11 and 12) which are bolted to the side plates 27 have a sloping 10 surface 38 which is parallel to the sloping surface 39 on the roller carriages 3. Between these two surfaces, which are faced with the non-corrodible tracks 40 and 41, is a train of rollers 42 which are connected by the links 43 and are retained 15 in correct position by the chain 44 which has one end rigidly secured to the roller carriage 3 by the clevis block 45 and has its opposite termination secured to the clevis block 46 which is adjustable by the studs 47. The reaction of the studs is 20 taken by the brackets 48 which are rigidly secured to the side frames 37. Inasmuch as the chain 44 is looped under the pinion 49 at the upper termination of the roller train between the wedge surfaces, relative motion between the roller 25 carriage 3 and side frame 37 will insure the correct positioning of the wedge rollers at all times.

A continuous roller train formed by the rollers 50 and links 51 (Figs. 8, 9 and 12) operates 30 around the continuous oval-shaped track formed by the roller carriage 3 and the idler beam 52. The surfaces upon which the rollers travel are faced by the non-corrodible tracks 53 on the roller carriages, and the non-corrodible tracks 54 on 35 the idler beams 52. The roller carriage units are slidably retained on the side frames 37 by the grooved plates 55 which are attached to the side frames parallel with the sloping surfaces 38 and 39. The adjustable brackets 56 which are grooved 40 to receive the guide strips 57 on the idler beams 52 also function to keep the roller carriage units centralized with respect to the side frames 37 and at the same time serve to reinforce the slender idler beams. The final factor in keeping the roller carriage units and side frames centralized is 45 the finished surfaces 58 and 59 on the inwardly extending flanges of the roller carriages 3. Contact between the finished surfaces 58 and 59 and the mating finished surfaces on the side frames 37 together with the other elements hereinbefore 50 described positively assures that the roller carriage unit will be centralized with the side frames, and at the same time allows the entire gate unit to be centralized by means of the guide plates 60 and guide strips 61. The shims 62 and 63 permit 55 adjustment of the guide plate 60 and the guide strip 61.

The gate unit rolls up and down vertically upon the non-corrodible tracks 64 which are attached 60 to the vertical members of the orifice frame 65 (Fig. 12) in the zone adjacent to the orifice, and are attached to the imbedded channels 66 above the orifice. A rectangular non-corrodible seat 67 is attached to the orifice frame 65 and a mating seat 68 is attached to the gate leaf 1 and side frames 37. It is the contacting of these two leafs which effects the sealing of the gate.

In order that the gate unit will be positively held against the roller tracks 64 while it is being 65 raised or lowered, non-corrodible T shaped slide bars 69 (Fig. 12) are inserted in the mating retaining brackets 70 which are secured to the side frames 37. The springs 71 impart a thrust upon the bars 69 which are in contact with the imbedded slide plates 72 and consequently impart 75

the spring reaction to the gate unit and hold the gate against the tracks 64. Another reason for providing these pressure contacting elements is to minimize the tendency for the gate to vibrate. When gates of the general type shown in this application are closed with water passing through the orifice there is a tendency for the gate to vibrate because of the turbulences and partial vacuum which are produced on the downstream face of the gate leaf; therefore, it is essential that 10 the gate leaf unit shall be rigidly retained within its guiding slot by some such method as the slide bar and springs. It has also been found efficacious to admit air to the downstream face of the gate leaf by an air duct in order to minimize the 15 vacuum thereon. The air duct 73 (Fig. 2) serves this purpose.

In all reservoirs there is a certain amount of waterlogged, submerged debris, such as leaves, twigs, and trees. In order that the small debris 20 which will not be screened out by the trashracks 74 (Fig. 2) will not collect on the roller trains and cause malfunctioning of the gate unit, a U-shaped shroud 75 has been attached to the idler beam 52, the shroud 76 (Fig. 9) has been 25 placed around the lower portion of the roller carriage 3, and another metal shroud 77 has been placed around the upper portion of the roller carriage. In addition to these shrouding elements it will be seen by examining Fig. 12 that 30 the construction is such that the grooved plate 55 also serves to exclude trash from the rollers 42, and that the general construction of the roller carriage elements is such that they inhibit the intrusion of foreign matter into the 35 roller trains.

The roller carriages 3 are bolted to the cross-head brackets 78 (Fig. 14) on the trunnion shafts 79. The crosshead brackets 78 are in turn bolted to, and serve as spacers for, the crosshead beams 40 80; thus it will be seen that the crosshead and roller carriages are in effect one unit and the gate leaf with the side frames form a second unit whose motion both vertically and horizontally is controlled by the crosshead and roller 45 carriage units.

It is necessary to exert a separating force between the crosshead and gate leaf units because of the sloping surfaces 39 and 38 on the roller carriage 3 and side frame members 37 respectively. These sloping surfaces are the means whereby the seat 67 on the orifice frame 65 and the seat 68 on the downstream face of the gate leaf 1 are brought into contact for sealing the opening and stopping the flow of water therethrough, or 50 for moving the gate leaf and seats horizontally out of contact with each other before the gate unit is raised so that there will be no sliding friction between the seating surfaces when the gate unit is being raised. When the roller carriage 60 units and crossheads are raised as shown on Figs. 8 and 14, the seats 67 and 68 will be out of contact, but when the crosshead and roller carriages are in the position with relation to the gate leaf as shown on Fig. 15, because of the effect of drawing the wedge surface on the roller carriages away from the gate leaf, the gate leaf unit will move downstream and the seats 67 and 68 will come into contact as shown on Fig. 12. It will be appreciated by those versed in mechanics that when water pressure of greater magnitude is present on the upstream face of the gate leaf 1 than is present on the downstream face of the gate leaf, there will be a tendency 65 to roll the gate leaf up the sloping surface 39 on 70 75 75

the roller carriage 3. The upward component thus produced, dependent upon the slop of the wedge plane, must be resisted by the weight of the gate; and if this component exceeds the weight of the gate leaf, some means which will exert an additional force between the crosshead and roller carriage unit and gate leaf unit must be employed in order for the gate to function properly. The design shown on Figs. 13 to 21 inclusive illustrates one method of securing this separating force, and the design shown on Figs. 22 to 25 illustrates an alternate method for accomplishing the same result.

In the first embodiment of this principle, the hoisting cable 5 is looped around the sheaves 81 (Figs. 14 and 17) which are mounted on the pins 82 through the inwardly extending portions of the levers 83. Inasmuch as a multiple part line is used for hoisting the gate, the sheaves 81 have corresponding sheaves 84 on the underside of the hoist frame 16 (Fig. 7). The sheaves 84 are mounted on the pins 85 which are supported by the plates 86, and are provided with the grease lines 87 for lubricating the anti-friction roller bearings 88 upon which they rotate. The mounting of the sheaves 81 (Figs. 18 and 19) shows the details of the sheaves and roller bearing mountings for both upper and lower sets of sheaves. The general method of mounting is well known to those skilled in the arts; but since the sheave assemblies are submerged in, or subject to, the intrusion of water or moisture, special sealing means are employed to exclude water from the bearings 88. These means consist of: a non-corrodible, spring-metal seal ring 89 (Fig. 19) which is set into an annular groove cut in the hub of the sheave, the resistance grooves 90, and the groove 91 in which a packing ring 92 is retained. It will be noted that the surfaces adjacent to these sealing means are so arranged that it is unnecessary to provide sealing units on all sheaves; for when the unit is assembled on the pin 82 with the cover disks 93 and nuts 94, each seal will bear firmly against the surface adjacent and thus effectively prevents the intrusion of water or moisture into the roller bearings 88. A means for greasing the rollers is provided by the drilled holes 95.

The fulcrum of the levers 83 is on the fulcrum pins 96 which are journaled in the cup bearings 97 (Fig. 20) on the cross-head beams 80. The levers 83 are welded to their respective hub elements 98 which are keyed to the fulcrum pins 96; hence all of the elements of both levers 83 comprise a rigid member. The links 99 (Figs. 14, 15 and 20) are connected by the pins 100 to the outwardly extending portions of the levers 83 and to the brackets 101 which are rigidly secured to the top of the gate leaf 1. The gear segments 102, which are mounted on the inward terminations of the lever arms 83, are provided to insure that both roller carriages will be raised in unison, since the connection between the crosshead and roller carriages is incapable of performing this duty. The condition of the roller carriage units not raising in unison might be encountered should one carriage tend to stick in the lower position; therefore, this provision has been made to prevent the damaging of the crosshead and carriage units which would result should the roller carriages not raise in unison.

It will be noticed that in order to protect the moving parts of the crosshead unit from the debris previously mentioned, cover plates 103 (Figs. 13 and 14) have been placed over the top

of the unit as well as the end plates 104 and 105, and the encasing boxes 106 and 107 on the underside of the crosshead beams 80.

In order that the functioning of the crosshead unit may be clearly understood, an operating cycle of the gate will now be described. Assume the gate to be in the upper position as shown on Fig. 3. The crosshead and roller carriage units will be in the position shown on Fig. 14, because the weight of the gate leaf 1, crosshead unit 2, and roller carriage units 3 will be suspended from the sheaves 84 on the underside of the hoist frame 16 and will be carried by the sheaves 81 on the inwardly extending portions of the levers 83. This arrangement will produce on the fulcrum pins 96 an upward force which is transmitted to the crosshead beams 80, and a downward force acting upon the gate leaf 1 through the links 99. The magnitude of these forces may be varied by changing the distance from the center to fulcrum of the lever arm employed. As the hoisting cable is payed off from the twin drums 6, the gate will be lowered until it comes to rest on the metal stops located on the bottom sill of the rectangular inlet orifice. When the gate has reached this position, the most acute tendency for the gate to roll up the sloping surface of the roller carriage is manifest, provided there is little or no water pressure on the downstream face of the gate leaf 1. An analysis of the forces will show why the gate leaf cannot roll upward on the sloping surface of the roller carriage. Inasmuch as there is a force tending to roll the gate leaf upward there must be an equal and opposite force tending to pull the roller carriages and crosshead unit downward. This downward force on the roller carriages plus the weight of the roller carriages and crosshead units is supported by the sheaves and hoisting cable, and, consequently, produces a force through the levers 83 which acts downward upon the gate leaf and thus offsets the tendency of the gate leaf to roll upward, since there is a net downward component in addition to its own weight, holding the gate leaf on the bottom sill of the orifice. Starting the condition from another angle, in order for the gate leaf to roll upward on the roller carriage the gate would have to lift itself against its own weight plus the downward component imposed through the levers and links by the crosshead and roller carriage units. A condition of this sort obviously cannot exist unless there is an actual buoyancy of the gate leaf which exceeds the weight of all of the parts comprising the orifice closure unit. Since the condition of equilibrium described exists until the roller carriages reach the end of their downward travel and the levers 83 with their component elements are in the position shown on Fig. 15, it is apparent that the gate leaf will not roll upward on the sloping surfaces on the roller carriages. As the roller carriages travel downward after the gate has come to rest on the bottom sill, the withdrawing of the sloping surfaces on the roller carriages will allow the springs 71 (Fig. 12) and the water pressure on the upstream side of the gate leaf 1 to move the gate horizontally downstream until the gate seat 68 bears against the orifice seat 67, and thus complete the closing cycle.

There is another contingency which must be taken into account in the design of gates of this type which are closed under unbalanced conditions. When water is flowing beneath the gate under conditions which approach those of a free discharge, there is a resulting drop in pressure

due to the velocity on the underside of the gate; but the downward force on the gate imposed by the water on the girders above is diminished very little if any. It is, therefore, evident that there will exist a downward component acting on the gate leaf due to the pressure differential which will exist between the head pressure acting upward on the bottom girder and the head pressure acting downward on the girders above. This additional downward component must be kept to a minimum in order to avoid providing greatly increased capacity of the hoisting unit. In the design which is illustrated on Figs. 8 and 10, the sloping plate 32 tends to restrict the orifice and maintains the pressure differential as low as design conditions will permit. In addition, the holes 33, 34 and 35 permit the pressure to more nearly equalize itself on the underside of the gate leaf. We do not claim that the design shown herein will eliminate the pressure differential; however, the design as illustrated does eliminate the possibility of a partial vacuum on the underside of the gate, and does more nearly equalize the differential pressure which will be present.

In the opening cycle of the gate, the circular penstock 108 (Fig. 2) as well as the transition section 109 will be filled with water through the by-pass line 110. When the pressure is equalized on both sides of the gate leaf, the gate unit is raised. This method of opening naturally assumes that a second gate, such as a turbine wicket gate or some other means of closure is present downstream from the orifice gate. Since these gates are generally employed as emergency gates, a second closing means is generally present in the penstock or conduit; however, it is to be understood that the gate unit can be raised as well as lowered under unbalanced conditions. The by-pass 110 is used where there is a second gate in order to prevent the impact on a second gate of a large volume of water which would enter the penstock or conduit, should the orifice gate be opened without filling the conduit or penstock between the gates.

In the alternate design shown on Figs. 22 to 25 inclusive, the roller carriage units are mounted on the pins 111 which are carried by mating bores in the roller carriage 3 and the crosshead brackets 112, (Fig. 23). The sheaves 113 are mounted on the pins 114 which are journaled in the trunnion bearings 115 on the crosshead beams 116. The secondary sets of sheaves 117 are carried on the pins 118 which are retained in mating holes in the bracket plates 119 attached to the gate leaf 1. A spacing spool 120 maintains the sheaves 117 in the proper alignment and the web plates 121 perform a similar function in that they align and give rigidity to the bracket plates 119. The sheave shields 122 and 123, and the cover plates 124 prevent the hoisting cable 5 from jumping out of the sheave grooves, should there be slack in the cable, and help to exclude foreign matter which might collect on the sheaves and impair their efficiency.

A rack 125 (Figs. 23 and 25) which is shown attached to one of the crosshead brackets 112 illustrates a means for positively insuring that both ends of the crosshead will raise in unison. The teeth on the rack 125 are in mesh with the dual pinions 126 which are rigidly keyed to the transverse shafts 127, journaled in the bearings 128; hence, if a rack were assembled on the opposite crosshead bracket 112 and engaged pinions which were rigidly keyed to the shafts 127, it is apparent that the crosshead would remain hori-

zontal while being raised or lowered. It is to be understood that the crosshead will raise horizontally unless one of the roller carriage units sticks; and it is for this contingency that it may be found advisable to include a squaring means, such as the rack and pinions which are illustrated.

In order that the manner in which this crosshead unit functions to produce a separating force between the crosshead and gate leaf 1, an analysis of the forces will now be made. Assume the weight of the gate leaf, crosshead and roller carriage is being supported on the hoisting cable 5. Inasmuch as the cable is continuous, and is provided with an equalizing means, the tension in the cable will be equal in all of the multiple parts which hoist the gate. It will be noticed that several parts of the hoisting cable are passed beneath the sheaves 113 and over the sheaves 117; therefore, the tension in the cable will produce forces tending to pull the sheaves 113 upward while equal and opposite forces will be produced which will exert a downward force on the sheaves 117. Since the downward force on the sheaves 117 is transmitted to the gate leaf 1 and the upward force on the sheaves is transmitted to the crosshead unit, it will be apparent that there will be established a separating force between the two elements. These forces will obviously be present at all times while there is tension in the hoisting cable; therefore, this arrangement will perform exactly the same duty as the design previously described. It will be equally apparent that by varying the number of sheaves 117 on the pins 118 the downward force upon the gate leaf 35 can be made to vary considerably.

By studying the two alternates it will be seen that the principle involved for producing the separating force is in each instance identical—it is only the method of execution that differs. We mention this in order that the flexibility of the principle will be appreciated. From this fact it will be apparent to those skilled in the arts that this application precludes illustrating, the many variations of elements and methods of reeving of the hoisting cable which can be made to produce the same result without departing from the spirit of our invention.

When the water surface is below the platform 129 (Figs. 1 and 2) the gate unit may be raised and supported on the beams 130 which are hinged and swing outward to form a support for the gate unit. With the gate unit in this position, it is accessible by descending the ladder 131 from the platform above and may be inspected, painted or serviced. When the water is above the surface of platform 129, under operating conditions the gate unit is dropped down slightly into the opening 132 as shown on Fig. 3 and thus forms a bulkhead and prevents waterlogged timbers which are generally present in reservoirs from entering the penstock or conduit through the opening 132.

Another feature of the structure is the manner in which debris collecting in the roller carriage pits 133 is expelled. It is essential that these pits be free of foreign matter when the gate is lowered, since the roller carriage units travel downward into this space during the lowering and seating of the gate unit. These pits are freed of debris by releasing compressed air into the bottom of the pits through the air lines 134. The air will agitate and exert a lift on the debris carrying it upward and into the path of the water passing through the orifice and allow it to be carried away.

While in the foregoing we have described specific embodiments of our invention, it is, nevertheless, to be understood in practicing the same we may resort to any and all modifications which fall within the scope of the appended claims defining the invention.

We claim:

1. In combination with a gateway, a drop gate member seating therein, cooperating inclined plane means for moving the gate member from a seated position while under pressure in advance of opening movement, cable means initiating the movement along the inclined plane means from the seated position and for accomplishing opening and closing travel of the gate member, and means resisting forces tending to move the gate upwardly on the inclined plane means as pressure builds up on one side thereof.
2. In combination with a gateway, a gate unit movable transversely of the way and including relatively movable parts one of which is a gate leaf, inclined plane means between the leaf and complementary parts for seating and unseating the gate leaf prior to opening and closing movement of the unit, and cable operated gate opening and closing mechanism affording flexible suspension for said unit and including cooperating means exerting a downward thrust on said gate leaf to relate the relative movement of the gate leaf and other gate unit parts.
3. In combination with a gateway, a gate unit movable transversely of the way and including relatively movable parts one of which is a gate leaf, inclined plane means between the leaf and complementary parts for seating and unseating the gate leaf prior to opening and closing movement of the unit, and cable operated gate opening and closing mechanism including multiple cooperating means relating the relative movement of the gate leaf and other gate unit parts to equally distribute the gate raising effort and oppose the tendency of said gate leaf to move upwardly due to pressure acting thereon.
4. In combination with a gateway, a gate unit movable transversely of the way and including relatively movable parts one of which is a gate leaf, inclined plane means between the leaf and complementary parts for seating and unseating the gate leaf prior to opening and closing movement of the unit, and gate opening and closing mechanism including cable means suspending said gate unit parts and cooperating synchronized means relating the relative movement of the gate

leaf and other gate unit parts to equally distribute the gate raising effort and oppose the tendency of said gate leaf to move upwardly due to pressure acting thereon.

5. In combination with a gateway, a gate unit movable transversely of the way and including relatively movable parts one of which is a gate leaf, inclined plane means between the leaf and complementary parts for seating and unseating the gate leaf prior to opening and closing movement of the unit, gate opening and closing mechanism including cable means for flexibly supporting said gate leaf and cooperating means relating the relative movement of the gate leaf and other gate unit parts for opening and closing movements of said unit, and means connected with said gate supporting means for arresting gate movement at any gate unit position.

6. In combination, a gateway and a gate leaf seating therein, a carriage on which said gate leaf is movable into open and closed positions transversely of said gateway, said gate leaf and carriage being relatively movable to seat and unseat said leaf, and cable means flexibly suspending said gate leaf through a jointed connection with said carriage structure.

7. In combination, a gateway and a gate leaf seating therein, a carriage on which said gate leaf is movable into open and closed positions transversely of said gateway, said gate leaf and carriage being relatively movable to seat and unseat said leaf, cable means suspending said carriage structure, and a flexible connection between said gate leaf and said carriage whereby a downward thrust is imposed on said gate leaf sufficient to overcome a lifting force on the leaf due to unbalanced pressure conditions on opposite sides thereof.

8. In combination, a gateway and a gate leaf seating therein, a carriage on which said gate leaf is movable into open and closed positions transversely of said gateway, said gate leaf and carriage being relatively movable to seat and unseat said leaf, and means flexibly suspending said gate leaf and carriage structure including connections with said gate leaf whereby a downward thrust is imposed on said gate leaf sufficient to overcome a lifting force on the leaf due to unbalanced pressure conditions on opposite sides thereof.

CERTIFICATE OF CORRECTION.

Patent No. 2,131,052.

September 27, 1938.

PHILLIP A. KINZIE, ET AL.

It is hereby certified that error appears in the printed specification of the above numbered patent requiring correction as follows: Page 3, first column, line 66, for the word "leafs" read seats; page 4, first column, line 36, for "grove" read groove; and that the said Letters Patent should be read with this correction therein that the same may conform to the record of the case in the Patent Office.

Signed and sealed this 13th day of December, A. D. 1938.

Henry Van Arsdale

(Seal)

Acting Commissioner of Patents.
